UNITED STATES PATENT OFFICE

THEODORE F. VON DORN, OF NEW YORK, N. Y.

TIE PLATE ANCHOR

Application filed November 20, 1930. Serial No. 497,005.

This invention pertains to a combined tie plate and rail anchor, especially designed for preventing the longitudinal creeping of railway track rails during the passage of the heavy rolling stock thereover.

The prime object of the invention is to provide simple, durable, economical, practical and effective means for the purpose.

A further object is to so construct my improved means that it may be easily and readily installed without any movement or interference with the track rails.

Another object of the invention is to so construct my combined tie plate and rail anchor that it may be readily installed in its proper position by driving the combined means beneath the rail, when the old tie plate shall have been removed.

Another object of the invention is to provide improved means serving to prevent any outward movement of the rail anchor under any and all conditions, and at the same time serving as a medium whereby the combined tie plate and anchor may be readily driven or forced to its proper position beneath and in contact with the track rail.

The foregoing and such other objects as may appear from the ensuing description are accomplished by the construction, combination, arrangement and location of the several parts hereinafter more fully described, illustrated by the accompanying drawings, and more particularly pointed out in the claims appended hereto, it being understood that slight changes in the precise form and minor details of the construction may be resorted to without departing from the spirit or sacrificing any of the advantages of the invention.

In the accompanying drawings forming a part of this specification it will be seen that:

Figure 1 is a plan view of the improved means constituting my invention.

Figure 2 is a longitudinal section taken 45 in the plane of the dotted lines 2-2, Fig. 1.

Figure 3 is a plan view of the tie plate removed from beneath the track rail.

Figure 4 is a perspective view of the rail anchor detached from the tie plate and track rail, and

Figure 5 is a detached perspective view of the means serving as an abutment stop for the anchor and as a means for receiving the driving on blows of a sledge or maul in forcing the tie plate and anchor in their installed position.

In the embodiment of my invention as illustrated, it will be seen that the numeral 1 designates a railway track rail, 2 a cross-tie broken away, 3 the tie plate seated on said cross-tie beneath the track rail, 4 the rail anchor adapted to be placed within the slotted portion of said tie plate, with the lower face of each of the members 5 resting in alignment with the lower face of the tie plate upon the upper surface of the cross-tie, while the upper portion 6 of said anchor is adapted to overlap the upper inclined face of the base flange of the track rail and rigidly and tightly clamp against said base flange when properly applied to the track rail as hereinafter described.

It will be perceived that the tie plate 3 is beveled or inclined gradually from each extreme outer end portion thereof to the points 7 intermediate its ends, and is provided intermediate its ends with a transverse upward extension or abutment member 8, said member being adapted to rest in contact with the outer edge of the base flange of the rail when said plate shall have been properly seated beneath the track rail. The said tie plate is also provided with two elongated slots 9 formed therethrough and four spike fastening openings 10 formed therethrough for the reception of the usual spike fastenings usually employed for securing the track rail to the cross-tie. Near one end portion of the tie plate 3 is formed therethrough an opening 11 preferably square in contour, said

opening being provided for the reception of the stem 12 of a member 13 preferably rectangular in contour, said member being adapted to rest in contact with the rear face 5 of the anchor member 4, thus serving as a stop or abutment to prevent under all conditions any outward movement of said anchor, and at the same time serving as a medium to receive the blows of a sledge or maul during 10 the operation of driving the combined tie plate and anchor into their properly installed position beneath the track rail.

In applying the combined means to a track rail to take the place of one of the old type 15 of tie plates, it is simply necessary to remove the old plate, then place the members 5 of the anchor 4 within the slotted portions of the tie plate with the rear face of the anchor resting in contact with the inner face of the 20 member 13, then place the tie plate on the cross-tie with the left hand beveled or inclined portion beneath one edge of the base flange of the track rail, then by striking the outer face of the member 13 with a suitable 25 sledge or maul the combined tie plate and anchor is forced beneath the rail into its proper position as shown in the drawings, with the overlapping portion 6 of the anchor in rigid and extremely tight contact with 30 the upper inclined face of the track rail base thereby preventing any tendency of the longitudinal creeping to said rail, while the lower face of the anchor and tie plate are firmly and securely seated on the upper face 35 of the cross-tie.

It will be understood that all of the several parts of this improved means may be formed from any suitable or desirable metal, and any desirable dimensions, that will best serve the 40 purposes for which it is intended, and while the stem 12 of the member 13 is preferably of round formation inserted in a square opening, with the lower end portion of said stem 12 upset or riveted in any suitable manner so that the metal of said lower end filling in the corners of the square opening to prevent any rotary movement of the member 13, as shown in Fig. 2 of the drawings, nevertheless, if desired, the stem 12 may be formed 50 square in contour so as to properly and snugly fit into the opening 11 formed through the tie plate for the reception of said stem or shank 12.

55 It will be perceived that the outer rear face of the anchor member 4 is provided with a vertically disposed portion that rests in close contact with the inner vertical face of the member 13 thereby maintaining said anchor member 4 in its locked position with relation to the tie plate and track rail and preventing any rearward movement of the member 4, or its accidental working outwardly above the tie plate, which could otherwise 60 be possible on account of the intense pres-

sure and vibrations caused by the passage of heavy rolling stock over the track rails.

Having thus described my invention, what I claim and desire to secure by Letters Patent is:

70 1. In a tie plate anchor, the combination of a tie plate provided with an abutment member and two elongated slots formed through said plate and member, an anchor member having its lower members fitted within said slots in contact with the lower face of a track rail, and a member rigidly secured to the tie plate resting against the rear face of said anchor member.

75 2. In a tie plate anchor, the combination with a tie plate having a transverse abutment member near one end portion thereof and two elongated slots formed through said plate and member, an anchor member fitted within said slots in contact with the lower face of a track rail, and a member rigidly secured to the tie plate at the rear of the anchor member with its inner face in contact with the outer face of said anchor.

80 3. In a tie plate anchor, the combination with a tie plate having an abutment formed on its upper face and provided with two elongated slots therethrough, an anchor formed with two members fitted within said slots with said members in contact with the lower face of a rail base, a square opening formed through the said plate, and a member rigidly secured within said opening with its inner face in contact with the outer face of said anchor.

85 4. In a tie plate rail anchor, the combination with a tie plate having an abutment member and two elongated slots formed through said plate and member, an anchor formed with two lower members fitted within said slots and an upper portion overlapping the upper face of a rail base, and a member rigidly secured to one end portion of the plate in contact with the upright rear face of said anchor.

90 5. In a tie plate anchor, the combination of a tie plate having two longitudinally disposed slots formed therethrough intermediate its ends, a rail anchor formed with two lower members fitted within said slots in contact with the lower face of the base of a rail and an upper overlapping member in rigid contact with the upper inclined face of said rail base, and a member rigidly secured near one end of the plate with its inner face in contact with the outer vertically disposed face of said anchor.

95 105 110 115 120 125 130 6. In a tie plate anchor, the combination with a tie plate formed with two longitudinally disposed slots formed therethrough, an anchor fitted within said slots and overlapping the upper face of the base of a rail, and a member rigidly secured to said plate at the rear of the anchor serving as a stop to the rearward movement of said anchor and as a

striking medium in forcing the plate and anchor into their proper installation.

7. In a tie plate rail anchor, the combination with a tie plate having two longitudinal slots formed therethrough, an anchor fitted within said slots and overlapping the upper face of a rail base, a member rigidly secured to the said plate at the rear of said anchor in contact with the outer face of the anchor and serving to prevent any outward movement of the anchor and serving to receive the blows of a sledge in driving the said plate into its proper installed position.
